24,599, Aug. 20, 1970. This application Aug. 10, 1971,
Ser. No. 170,676

Claims priority, application Germany Feb. 20, 1970

Term of patent 14 years

Int. Cl. D3—03

U.S. Cl. D88—3 A

FIG. 1

FIG. 4

FIG. 2

FIG. 3

FIG. 5

FIG. 1 is a top plan view of an umbrella runner with lever showing my new design;

FIG. 2 is a side elevational view thereof the opposite side being a mirror image thereto;

FIG. 3 is a right side elevational view of FIG. 2;

FIG. 4 is a left side elevational view of FIG. 2; and

FIG. 5 is a bottom plan view thereof.

This application is a continuation of Ser. No. D. 24,599, filed Aug. 20, 1970, and now abandoned.

I claim:

The ornamental design for an umbrella runner with lever, as shown and described.
